UNITED STATES PATENT OFFICE.

MAX PRILUKER, OF NEW YORK, N. Y.

MASK.

1,417,201.

Specification of Letters Patent. Patented May 23, 1922.

Application filed April 26, 1921. Serial No. 464,615.

To all whom it may concern:

Be it known that I, MAX PRILUKER, a citizen of the United States, residing at New York, in the county of New York and

5 State of New York, have invented certain new and useful Improvements in Masks, of which the following is a specification.

The present invention relates to devices for securing elastic cords and the like to 10 masks or similar devices, and the object is to provide an exceedingly simple coupling element that may be cheaply manufactured, can be quickly and effectively secured to the cord, and also easily engaged with the mask.

15 In the accompanying drawings:

Figure 1 is a perspective view showing the application of the device.

Figure 2 is a plan view of the coupling blank,

20 Figure 3 is a perspective view on an enlarged scale, showing the structural features.

In the embodiment disclosed, the blank is preferably composed of a flat piece of 25 sheet metal that may be easily bent and comprises a rectangular body portion 3, from one end of which a longitudinally disposed narrow tongue 4 projects, the end of the body portion on opposite sides of said 30 tongue forming stop shoulders 5. The body is provided between its ends and in its opposite side margins with notches 6, thereby producing side wing portions 7, and between these wing portions are formed indentations 35 producing spurs 8.

In applying the coupling to an elastic cord or the like, a portion of which is shown at 9, the wings 7 are bent around the cord, forming a tubular cord-enclosing portion

so that the spurs 8 are embedded therein. 40 The tongue 4 is passed through the margin of the mask in a manner readily understood and is then bent to form a hook.

From the foregoing, it is thought that the construction, operation and many advantages of the herein described invention will be apparent to those skilled in the art, without further description, and it will be understood that various changes in the size, 45 shape, proportion and minor details of construction may be resorted to without departing from the spirit or sacrificing any of the advantages of the invention.

Having thus fully described my invention, what I claim as new, and desire to secure by 55 Letters Patent, is:

A device for coupling cords to masks and the like, comprising a flat blank of sheet metal having a body portion of substantially the same width throughout and having notches in its opposite margins, a tongue portion extending from one end and narrower than the body portion, forming stop shoulders, said tongue portion adapted to be bent to form an article engaging hook, the 60 portion of the blank between the notches and the end opposite the tongue being adapted to be bent into cylindrical shape to engage a cord, and having indentations on one side forming spurs on the other side which 65 70 also engages the cord.

In testimony whereof, I affix my signature in the presence of two witnesses.

MAX PRILUKER.

Witnesses:

LILLIAN PRILUKER,
MAY MICHAELS.
